ATTACHMENT FOR STAPLING MACHINES

John Thomas Dalton, Durham, N. C., assignor to
 Golden Belt Manufacturing Company, Inc.,
 Durham, N. C., a corporation of New Jersey

Application December 31, 1938, Serial No. 248,709

14 Claims.

(Cl. 1—2)

This invention relates to wire stitchers or stapling machines and more particularly to a feeding attachment for a wire stitcher or stapling machine.

5 In my copending application, Serial No. 234,916, filed October 14, 1938, I have disclosed and claimed mechanism for attaching a tag to the string of a bag, such as a tobacco bag. The mechanism disclosed therein includes means for 10 delivering the bags to the stitching machine and arranging the string on the anvil of the stitching machine and means for feeding tags to the anvil, the operation of the parts being coordinated with the operation of the stitcher head.

15 The present invention relates more specifically to the bag feeding mechanism. In the machine forming the subject matter of the present application, I employ the mechanism disclosed and claimed in the said copending application to feed tags to the anvil with a step by step movement coordinated with the operation of the stitching machine, or any other suitable means for so feeding the tags. In place of the bag feeding mechanism disclosed in my copending application, I employ a rotary table having means 20 for holding bags and having a flange or edge provided with guides to receive the strings of the bags and properly position them for feeding to the anvil of the stitching machine.

25 The invention further comprises means for engaging the string of a bag, as the feed table rotates and guiding it to the anvil in position to be stitched to a tag.

30 In the accompanying drawings I have shown one embodiment of the invention. In this showing:

Fig. 1 is a perspective view of a wire stitching machine showing tag feeding means and also showing the rotary feed table for the bags;

35 Fig. 2 is a skeleton perspective view with the feed table shown in dotted lines showing the various drive mechanism;

40 Fig. 3 is a detailed, sectional view of a portion of the feed table showing the means for holding the bag strings during the feeding operation;

45 Fig. 4 is a detailed view of a portion of the mechanism for feeding individual strings to the anvil;

50 Fig. 5 is a plan view of a portion of the feed table;

Fig. 6 is a detailed, perspective view of drive mechanism for the hook which engages the bag string and feeds it over the anvil;

55 Fig. 7 is a detailed view of a string combing mechanism;

Fig. 8 is a perspective view of the stitcher head and anvil showing the position of the tag and string prior to the stitching operation;

Fig. 9 is a detailed view of another string combing mechanism forming a part of the present machine;

Fig. 10 is a side elevation of the feed table, stitcher head and anvil showing the relative positions of these members and the string guiding members; and

Fig. 11 is a plan view of the parts shown in Fig. 10.

The apparatus forming the subject matter of the present application, in its broadest aspects, comprises a frame A, a wire stitcher B, a rotary feed table C for the bags and a tag feeding mechanism E.

The frame may be of any suitable construction for supporting the various parts and preferably consists of a table 1 and suitable legs 2. 20 The rotary feed table is supported on an auxiliary frame 3.

The wire stitching machine may be of any suitable construction, for instance, such as is shown in the patent to Maynard, No. 1,302,402. 25 A detailed description thereof is therefore believed to be unnecessary.

As shown in Fig. 1, the wire stitching mechanism may comprise a suitable stitching head 4 mounted on an arm 5 secured to the bed of the machine by bolts arranged in flanges 6 on the base of the wire stitcher. It may be driven by a motor 7 whose shaft carries a pinion 8 (see Fig. 2) meshing with a gear 9 mounted on the main shaft (not shown) of the wire stitching machine, 35 which shaft extends through the horizontal portion of the arm 4.

As shown in Fig. 8 an anvil 10 is arranged beneath the stitcher head 4. The stitcher head carries a reel 11 upon which is mounted a coil of wire 12 and the wire is fed from this coil through a guide tube 13 into the stitcher head. A tag 14 is delivered to the anvil by suitable tag feeding mechanism having a step by step movement coordinated with the operation of the stitcher head to deliver a tag to the anvil between each two descents of the stitcher head. At the same time a bag 15 is fed into position whereby one of its strings 16 may be arranged over the anvil to stitch the tag to it.

The bag feeding mechanism comprises a table 17 rotatably mounted upon a shaft 18, the table being arranged horizontally and the shaft vertically. The table is rotated at the proper speed for the delivery of the bags to the anvil of the 55

stitching machine by a worm gear 19 meshing with a worm 20 carried by a shaft 30. The shaft 30 is driven from the main shaft of the stitching machine by drive mechanism shown in Fig. 2 of the drawings. As shown, the shaft of the stitching machine which carries the gear 9 is provided with a sprocket 31 adapted to receive a chain 32. This chain passes over another sprocket 33 arranged on a shaft 34. Shaft 10 34 may also be provided with a hand wheel 35 to permit manual operation of the machine. Shaft 34 extends forwardly and drives a main drive shaft 36 through suitable bevel gears 37 and 38. Shaft 36 is provided with a sprocket 39 and shaft 30 is provided with aligned sprocket 40. A chain 41 passes over these two shafts to drive the worm shaft 30 from the main shaft 36. The bag feeding table 17 is provided with a groove 42 adjacent its edge and a guide plate or 20 ring 43 is arranged in this groove. Another plate 44 is arranged at the edge of the table. The plate 43 is provided with a flat top to support the string end of the bags and the plate 44 is provided with spaced notches 46. The surface of the table is provided with an inner row of pegs 47 arranged in pairs as shown in Fig. 5 and with an outer row of pegs 48. The bags are placed on the table by an operator standing at the side of the table opposite the stitcher 25 head, a bundle of bags being placed between a pair of pins 47 with substantially half of the bundle extending on one side of the corresponding pin 48 and the other half extending on the other side of the pin. The bags are arranged 30 with their sides supported on the ring 43 and the string loop at one side of the bags are then fed through the notches 46 as shown in Fig. 3 of the drawings. The string loop at the other side of the bag hangs in front of the top or mouth of 35 the bag as shown in Figs. 3, 8 and 10 of the drawings.

A string separating member is arranged along the front of the stitching machine to receive each string as the machine operates and deliver 40 it into position to be fed to the anvil. The position of this member is shown in Fig. 2 of the drawings and the construction thereof is shown in Fig. 4. As shown, a shaft 60 is provided with a sprocket wheel 61 upon its end which is aligned 45 with a sprocket wheel 62 mounted on the main shaft 36 and a sprocket chain 63 passes over these sprocket wheels to drive the shaft 60. The shaft 60 is mounted in suitable bearings on the frame of the machine (as shown at 60') and has 50 an enlargement 64 arranged on its end adjacent the anvil 10. This enlargement is provided with a substantially spiral groove 65. The enlargement 64 in the spiral groove is arranged over the portion of the table between the plates 43 and 55 44 in such position that the looped strings 16 are received in the groove 65 as the feed table rotates and each looped string rides along the under side of the groove 65 to the outer end 65' of the enlargement. The shaft 60 is provided with a longitudinal groove 66 in which rides a string 60 engaging member which carries the string over the anvil. The string engaging member is shown in Fig. 6 of the drawings. As shown, the shaft 36 drives a shaft 67 arranged adjacent to 65 and parallel to the shaft 36 through suitable gears 68. Shaft 36 is provided with a cam member 69 having a cam groove for the reception of a pair of rollers 70. The rollers 70 are carried by a reciprocating member 71 mounted in suitable guides 72 on the frame of the ma-

chine. The reciprocating member carries a curved arm 73 on its end, this arm being pivotally mounted on the reciprocating member at 74 and carrying a bag engaging arm 75 on its free end. As shown, the end of the arm 75 is 5 forked to engage the string of the bag, the hook 76 traveling in the groove 66 during the reciprocation of the reciprocating member 71 and being oscillated to carry the string over the anvil at the end of the reciprocation. Arm 75 is oscillated by means of a shaft 77 which is carried by the reciprocating member and is provided with an elongated gear 78. This gear meshes with a rack 79 traveling in suitable guides 80 carried by a plate 81 secured to the frame of the machine. The rack is actuated by means of a cam 82 mounted on the shaft 61, the cam having a groove for the reception of a roller 83 carried by an arm 84. The arm is pivoted on the frame of the machine as indicated at 85. Arm 84 is 20 connected to the rack by a link 86. The end of oscillating shaft 77 is provided with a crank 89 which is connected to the curved arm 73 by link 88 at a point adjacent the pivot 74. The connection of the oscillating shaft 77 to the curved arm 73 at a point near the pivot gives a wide swinging oscillation to the hook 76 upon slight movement of the shaft 77. Reciprocating member 71 is also provided with an upwardly extending arm 80 at its forward edge carrying an arm 80 having a notch 81 on its outer end to engage the side of a tag 14 as shown in Fig. 6 of the drawings and properly position it on the anvil for the stitching operation.

After the tag has been stitched to the bag 35 string, the strings are combed away from the anvil by combing mechanism shown in Fig. 7 of the drawings. A bar 102 (see Fig. 6) is secured to the reciprocating member and extends across the front of the stitching machine in front of the anvil. This bar 102 engages a stud arm 103 mounted on a lever 104. The lever 104 is pivoted to a stationary arm 105 carried by the frame of the machine intermediate its ends as indicated at 106. The other end of the lever 104 is connected to a link 107 which extends across the machine adjacent the anvil and is in turn pivoted to a link 108. Link 108 is pivotally mounted on the stitcher head at 109. Link 107 is provided with a pin 110 which forms a pivot for a combing arm 111, the combing arm 111 having a notch or tooth 112 adjacent one end. A spring 113 is arranged on the pivot pin 110 and is secured to the pin and the link 107 to normally tend to cause the combing arm to move 40 in a clockwise direction. Movement of the combing device is limited by a pin 114 carried by the link 107 and engaging a hook 115 on the end of the combing arm opposite the tooth 112. The combing arm is also provided with an extension 116 on its upper surface adapted to engage a projection 117 mounted on the stitching machine to move the combing arm in a counter-clockwise direction against the tension of spring 113.

The operation of the combing arm is as follows: When bar 102 moves to the left in Fig. 7 of the drawings, it swings the lever 104 on its pivot and moves the link 107 to the right. As the arm 107 moves to the right, extension 117 50 engages projection 115, revolving the combing arm 111 counter-clockwise against the tension of spring 113. At the end of this movement, bar 102 moves in a reverse direction and lever 104 is returned to its initial position by a spring 120. 55

secured to the lower end of lever 104 and to the frame of the machine (see Fig. 2). This moves the link 107 to the left in Fig. 7 of the drawings, and as soon as the extension 116 of the combing arm moves away from the projection 117, spring 113 swings the combing arm in a clockwise direction moving the end with the tooth or notch 112 downwardly in an arc and causing it to engage the string of the bag just stitched and carry it away from the anvil.

The machine further comprises a combing device which cooperates with the separating member 64 and the hook 76 to deliver the looped string to the anvil (see Figs. 9 and 10). The details of this device are shown in Fig. 9 of the drawings. The relative positions of the members 64 and 76 and the combing device are shown in Figs. 10 and 11 of the drawings. As shown, main drive shaft 36 is provided with a bevel gear 130 which meshes with a bevel gear 131 on a shaft 132 (see Fig. 6). Shaft 132 is provided with a cam 133 engaging an arm 134 (see Fig. 9). Arm 134 is provided with a curved end 135 adapted to receive a pivot pin 136 carried in a bracket 137 on the frame of the machine. The opposite end of the arm 134 is provided with a slot 138 for the reception of suitable fastening means passing through a vertically extending member 139. The provision of the slot 138 permits adjustment of the arm 139 and the combing member carried thereby. As shown, the upper end of the member 139 carries a substantially horizontal combing arm 140 having a tooth or notch 141 at its outer end. The operation of this device will be apparent. As each lower looped string 16 is separately fed through the groove 65 of the separating member and reaches the end of the groove, the notch 141 picks up the looped string and elevates it to a height sufficient that the hook 76, travelling in the groove 66 of the spiral member catches the string in its forked end and carries it over the tag and anvil for the stapling operation.

The tag feeding mechanism may consist of any suitable means for feeding tags singly to the anvil 10 and coordinating the feed with the operation of the stitcher head. Suitable means for this purpose are described in my copending application heretofore referred to and parts are illustrated herein although the details of the feed mechanism are not so illustrated. As shown, the tags may be arranged in a tube 150 which has an internal diameter substantially equal to the diameter of the tags so that the tags are arranged in stacked formation or in a column. A plate 151 is arranged on top of the tube and is provided with an opening of the same diameter as the interior of the tube. A hopper 152 is mounted on this plate, the hopper being of greater diameter than the tube and the opening in the plate. This hopper is adapted to be oscillated to deliver tags into the tube 150. As shown, a collar 153 surrounds the hopper adjacent the plate 151 and this collar is carried by an arm 154 which is connected to an oscillating arm 155. Arm 155 is eccentrically connected to a pair of discs 156 and 157. These discs are mounted on shafts 158 and 159, respectively. Shaft 159 is provided with a bevel gear 160 on its lower end meshing with a bevel gear 161 on the shaft 67 and shaft 158 is driven from the shaft 67 by similar bevel gears (not shown).

The tags are delivered singly from the bottom of tube 150 by suitable tag feeding mechanism (not shown) to the anvil 10. The delivery of the

tags is coordinated with the operation of the stitcher head so that a single tag is delivered to the anvil between each two descents of the stitcher head. An operator stands at the side of the rotary table opposite the stitcher head and places the bags on the table, a bundle of bags being arranged between a pair of the pegs 47 and around one of the pegs 48 as shown in Fig. 5 of the drawings. The strings on the side of the bag at the bottom are passed through the slots 46 and arranged as shown in Fig. 3 of the drawings. As the table 17 rotates, each bag string in the notches 46 rides along the under side of the groove 65 and is separated from the other looped strings. When it reaches the end of the groove 15 the hook or notch 141 which is arranged over the edge of the table, as shown in Figs. 9 and 10 of the drawings, engages the string and elevates it to a point where it will be engaged by the hook 76. As the hook 76 reciprocates toward the anvil 20 the groove 66 is in the position shown in Figs. 10 and 11 of the drawings and hook 76 rides through the groove 66 to receive the string that has been elevated by the combing device. Hook 76 then carries the lower looped string over the anvil to the position shown in Fig. 8 of the drawings. The stitcher head then descends and stitches the tag to the string 16. When the reciprocating member 71 moves forwardly, arm 100 engages the tag 14 to swing it around into proper position for the stitching operation. The bags with the strings attached thereto are carried around on the table away from the anvil and are removed from the table by an attendant.

The combing arm 111, being rotated in a counter-clockwise direction to raise the hooked end 112 when the reciprocating member 71 travels to its operative position is released upon the rearward movement of reciprocating member 71 and spring 120 swings arm 124 on its pivot to move the link 107 and the combing arm to the left in Fig. 7 of the drawings. This releases the projection 116 of the combing arm from the lug 117 and permits the spring 113 to swing the combing arm in a clockwise direction whereby the hooked 45 end or notch 112 engages the bag string 16 to which a tag has been stitched and removes it from the anvil.

I claim:

1. In combination with a wire stitching machine, a rotary table adapted to feed bags of the string closure type to the anvil of the stitching machine, spaced members arranged on the table for supporting a plurality of bags between pairs of said members with the bag strings arranged at the edge of the table, means for separating and positioning the strings of the bags, and string guiding mechanism to position a string of a bag over the anvil.

2. In combination with a wire stitching machine, a rotary table adapted to feed bags of the string closure type to the anvil of the stitching machine, spaced members mounted on the table for supporting a plurality of bags between pairs of said members with the bag strings arranged adjacent the edge of the table, the edge of the table being provided with a plurality of notches for separating and positioning the strings of the bags, and string guiding mechanism to position a string of a bag over the anvil.

3. In combination with a wire stitching machine, a rotary table adapted to feed bags of the string closure type to the anvil of the stitching machine, spaced members mounted on the table for supporting a plurality of bags between pairs

- of said members with the strings of the bags arranged adjacent the edge of the table, a member mounted on the edge of the table having notches therein for receiving the bag strings to 5 separate the strings of each bag from the strings of adjacent bags, and string guiding mechanism to position a string of a bag over the anvil.
4. In combination with a wire stitching machine, a rotary table adapted to feed bags of the 10 string closure type to the anvil of the stitching machine, and a rotating member arranged adjacent the anvil having a spiral groove for the reception of the bag string.
5. In combination with a wire stitching machine, a rotary table adapted to feed bags of the 15 string closure type to the anvil of the stitching machine, a hook arranged near the anvil to engage the bag string and feed it over the anvil, and means for reciprocating and oscillating said hook.
6. In combination with a wire stitching machine, a rotary table adapted to feed bags of the 20 string closure type to the anvil of the stitching machine, means for separating and positioning the bag strings on said table, a hook for feeding the bag string over the anvil of the stitching machine, and means for reciprocating and oscillating said hook.
7. In combination with a wire stitching machine, a rotary table adapted to feed bags to the 25 anvil of the stitching machine, means on the table for separating and positioning the strings of the bags, a reciprocating member arranged adjacent the anvil of the stitching machine, a hook carried by the reciprocating member 30 adapted to engage a bag string and carry it over the anvil, and means for oscillating said hook.
8. In combination with a wire stitching machine, a rotary table adapted to feed bags of the 35 string closure type to the anvil of the stitching machine, a rotating member having a spiral groove for the reception of a bag string, and an oscillating member adapted to engage and retain a bag string displaced from said rotating member.
45. 9. In combination with a wire stitching machine, a rotary table adapted to feed bags of the string closure type to the anvil of the stitching machine, a hook to engage a bag string and feed

it over the anvil, and a combing device to remove the bag string from the anvil after the stitching operation.

10. In combination with a wire stitching machine, a rotary table adapted to feed bags of the 5 string closure type to the anvil of the stitching machine, means for separating and supporting the strings of the bags, a hook to engage a bag string and feed it over the anvil, and a combing device to remove the bag string from the vicinity 10 of the anvil after the stitching operation.

11. In combination with a wire stitching machine, a rotary table adapted to feed bags of the string closure type to the anvil of the stitching machine, means on the table for separating 15 and supporting the bag strings, a reciprocating member arranged adjacent the anvil, an oscillating hook mounted on said member and adapted to engage a bag string and feed it over the anvil, and a combing device to remove the 20 bag string from the anvil after the stitching operation.

12. In combination with a wire stitching machine, a rotary table adapted to feed bags of the string closure type to the anvil of the stitching 25 machine, means for feeding the string of the bag over the anvil, and a combing device for removing the string from the anvil after the stitching operation.

13. In combination with a wire stitching machine, a rotary table adapted to feed bags of the string closure type to the anvil of the stitching 30 machine, a reciprocating member arranged adjacent the anvil, an arm carried by said member having a notch to engage a bag string and 35 remove it from the anvil, and means for actuating said arm.

14. In combination with a wire stitching machine, a rotary table adapted to feed bags of the string closure type to the anvil of the stitching 40 machine, a reciprocating member arranged adjacent the anvil, an arm pivoted on said member, said arm being provided with a notch, a spring to normally retain the arm in one position, and means for swinging the arm on its pivot when 45 said member is reciprocated to remove the bag string from the anvil after the stitching operation.

JOHN THOMAS DALTON.
